JOHN M. MILLER, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

VOLUME CONTROL

Application filed June 28, 1928. Serial No. 289,012.

My invention relates to the control of volume or magnitude of amplification in radio receiving systems, and more particularly those in which the source of power for the 5 anode circuits and cathode heating is of the alternating current type.

In accordance with my invention a resistance suitably related to a coupling element or transformer to effect volume control, 10 is characterized by the fact that it is comprised of coil layers or windings of bare resistance conductor disposed with the turns of one contacting, overlying and crossing or intersecting those of another; preferably the 15 layers or coils are reversely wound, in the sense that the conductor helices progress axially in opposite directions; and, preferably, the pitch, or spacing between turns, is different in or for the different layers or 20 coils. More specifically, an end of resistance wire is secured to a suitable form, as a thin strip of flexible insulating material, as intermediate its ends, and after the wire is wound thereon with a variable or fixed pitch or spacing 25 towards one end of the form, the direction of winding is changed and the wire with same or different and preferably lesser pitch or spacing is wound back over and upon the first winding or layer.

Further in accordance with my invention, the resistance described is one of several components of a resistance unit and is that section corresponding to and producing control 30 in the low volume region; more specifically, the unit comprises at least two other sections and the spacing of turns is the greater in that of the two sections nearest to the low volume section; preferably the lengths or resistances of the sections with respect to each other and 35 to the total resistance are such that the percent change in resistance, as a co-operating control contact moves from one section to another, is suitably small to avoid clicks or like noises in the loud speaker.

My invention resides in the method and apparatus hereinafter described and claimed.

For an understanding of some of the various forms my invention may take, reference is to be had to the accompanying drawings 50 in which:

Fig. 1 is a diagrammatic view of a receiving system embodying my invention.

Fig. 2 is a side elevational view of a resistance unit.

Fig. 3 is a diagrammatic view of mechanism for winding the resistance unit of Fig. 2.

Figs. 4 and 4^a are side elevational views of a modified form of resistance unit in different steps of its manufacture.

Fig. 5 is an elevational view, partly in section, illustrative of the mounting of the resistance unit and its co-acting control contact.

Fig. 6 is an end elevational view of the structure shown in Fig. 5.

Fig. 7 is a fragmentary view of a further modified form.

Referring to Fig. 1, the received electro-radiant energy is absorbed by the antenna A or other equivalent absorption structure. In 70 the example illustrated V is a thermionic radio frequency amplifier tube utilized as a coupling tube in the first stage of a cascade of radio frequency amplifying, detecting and audio frequency amplifying tubes. Its grid 75 g is connected to a terminal of coupling element or transformer T while its cathode or filament f is connected to earth or counter capacity E through the condensers k which exhibit low reactance at the radio frequencies involved. The transformer T may be an auto-transformer having a step-up ratio substantially as described and claimed in co-pending Miller application Serial No. 263,272, filed March 21, 1928.

In the circuit of the anode or plate a of the tube V is the primary P of a radio frequency transformer T¹, preferably having high step-up ratio and whose secondary S is shunted by the variable tuning condenser C. The secondary S and the condenser C may be included, in the usual manner, in the input circuit of a succeeding tube, as a radio frequency amplifier. After detection of the signal energy, it may be amplified at audio frequency and supplied to 90 a loud-speaking device, not shown.

G represents generically any source of 60 cycle alternating current, connected to the primary of the transformer T². A secondary winding of the transformer supplies so-called 100

"raw" alternating current to the filament or heating element f of the tube V , and of other tubes not shown. B represents a source of anode circuit current, which too may be derived from source G through a rectifier-filter system. The resistance R^1 , which is common to the input and output circuits of the tube V , and is traversed by the direct current flowing into the anode circuit, serves to bias the grid g to a suitable negative potential.

The volume control resistance R^2 is preferably connected, as shown, with one terminal connected by conductor 26 to winding T at the antenna connection thereto, and with its other terminal connected through conductor 26^a to that terminal of winding T remote from grid g .

Movable along the resistance is the control contact K connected by conductor 32 to earth E . By moving the contact K along the resistance R^2 there is produced a variable effect upon the input system of the tube V , which decreases the signal potential impressed upon grid g as the contact K is moved toward the antenna connection to the transformer T , as viewed in Fig. 1, and vice versa. According to the signal energy impressed upon the tube V is varied, with resultant control of the amplitude of signal energy in the output circuit thereof and ultimately in the volume of sound emitted by the loud speaker.

This type of control of volume is particularly adapted for use in radio receiving sets utilizing thermionic tubes one or more of whose electrode circuits are energized from a source of alternating current; in such receiving sets, to avoid hum, it is desirable to procure volume control without recourse to control of filament or heater current, and without recourse to control of anode current.

The conductor of the resistance R^2 is preferably of high specific resistance, such as Advance wire, or the like. The spacing of the turns, however, is different at different portions along the resistance R^2 from its end 1 to its end 2. In the example illustrated, resistance R^2 comprises three serially connected sections r^1 , r^2 and r^3 , as indicated in Fig. 2. The turns of section r^1 are closely spaced and those of r^2 more widely spaced. Section r^3 consists of a small number of turns c , as 6 or 7, widely spaced, of wire over which is wound a greater number of turns d , continuous with section r^2 . Both layers are of bare wire and in contact with each other. The turns c and d are not parallel, but intersect or cross each other, and where they cross they electrically contact with each other. The effect of moving the contact K along the edge of section r^3 , is substantially similar to that of moving the contact continuously along the coarsely spaced turns c with gradual and smooth change of resistance. It is impractical or undesirable because of considerations of space

and structure to maintain engagement of contact K with and along the wire c . With the turns of the conductor d , spaced considerably closer than and overlying and crossing the turns of c , engagement of the contact K with the successive turns of d amounts to successive connections between the contact K and numerous points along the conductor c through numerous successive resistance conductors, each a part of the conductor d and extending from the edge of the unit to the point of intersection and contact with conductor c .

As indicated in Fig. 2, the conductor of the resistance R^2 is wound in the form of a helix upon the thin or flat strip, plate or form 3 of insulating material. As indicated the sections r^1 and r^2 have their turn differently spaced, and r^3 comprises wire c having in effect a large number of taps d therefrom, with the result that per unit length along the edge of unit R^2 the resistance change is greatest in section r^1 , less in section r^2 , and still less in section r^3 . For example, the section r^1 may be 4 $\frac{1}{4}$ inches long, 120 turns per inch; the section r^2 may be $\frac{3}{8}$ of an inch long, 60 turns per inch, and section r^3 one inch long, layer c 7 $\frac{1}{2}$ turns per inch, underlying and contacting at intervals with coil d 60 turns per inch. The spacing of the turns of a section need not be uniform throughout but may, for example, increase as section r^3 is approached, as in co-pending application Serial No. 249,785, filed January 27, 1928. The conductor throughout the several sections may be Advance or other suitable wire, about No. 34 B and S gauge. When the strip 3 is $\frac{1}{2}$ inch wide and about $\frac{1}{16}$ of an inch thick, the entire resistance of the three sections is about 530 ohms.

The resistance R^2 of Fig. 2 is wound by looping one end of resistance wire through a hole 4 spaced a suitable distance from the end 1 of the strip 3, and a suitable number of widely spaced turns c are wound on the form towards the end 1, whereupon the direction of winding is reversed toward end 2 and the turns d are more closely spaced during winding over the underlying conductor layer c , to complete section r^3 ; and winding d is continued to form the section r^2 ; thereafter the pitch is further decreased, to produce greater resistance change per unit of movement of contact K , and the winding is continued towards the end 2 of the strip where the end of the resistance wire is looped through a hole 5 or otherwise suitably anchored, so completing section r^1 . The end clips 6, 6 of thin conducting material and having bent over ears 6^a, 6^a, are then clipped over the respective ends of the form, the holes 7, 7 thereof in register with the holes 8, 8 of the strip 3 and with the inner edge of the right hand clip 6 preferably in contact with the last turn of coil c of resistance section r^3 , substantially at the point at which

it passes over that edge of the resistance unit with which contact K is in engagement.

The resistance R^2 is conveniently wound by holding and rotating the form 3 between and by two rotatable spindles 9 and 10, Fig. 3, and at least one of which is driven, as by a motor M, through gears 11, 12, 13 and 14. On the shaft of gear 12 may be mounted a lead or master screw N having two connected threads, D, for section r^1 , E of different pitch for section r^2 and for outer layer d of section r^3 , both of the same direction of advance; a third thread C of coarser pitch, for inner layer c of r^3 . The several threads are in series or tandem, in that their adjoining ends communicate. An operator, in winding resistance R^2 , loops an end of resistance wire from the spool s through hole 4 of form 3 as above described. The wire is permitted to rest in the left end of thread C. The wire, guided by the thread C, is wound from left to right, to form inner layer c; the wire is next guided by thread E and advanced toward the left to form outer layer d and section r^2 , then the wire is guided by thread D, continuing to the left, to form section r^2 . The unit may be wound beginning at hole 5 and terminating at hole 4, in which event coil c of section 43 will overlie coil d thereof.

The spacing of d is great enough to permit c to enter between neighboring turns into engagement with edge of form 3.

In lieu of winding the section r^3 of a single piece of conductor, it may be wound of two separate pieces. Referring to Fig. 4, the coil c of the section r^3 may be a separate piece of conductor beginning at hole 4 and terminating at hole 4^a near the end 1 of the resistance unit. The second piece of conductor may be looped through the hole 4^a and wound thereover in the same or reversed sense, which latter is indicated in Fig. 4^a. As a further modification the coil c, of separate conductor, may be wound overlying coil d.

The resistance unit of Fig. 2, or of Fig. 4^a, may be suitably mounted with relation to its control contact K as indicated in Figs. 5 and 6. A circular housing or casing 20, preferably of molded insulating material, such as bakelite, has an integral top 21 and base flange 22. Integral with the top is an annular ridge 23 spaced from the wall 20 to form an annular groove in which is set the resistance unit by bending it into circular form. The ends of the strip 3 are secured by bolts or screws 24 and 25 which constitute the terminals with which connect connecting conductors 26, and 26^a. The rotatable operating knob 27 is secured to the shaft 28 which has a bearing carried by the top 21. Secured to the metallic shaft 28 is the contact arm 29 whose outer end constitutes the contact K which is movable along an edge of

the resistance unit. A conducting member 30 maintains electrical contact with shaft 28 and therefore with contact K, and has its outer end secured to the casing 20 by the nut 31 which also serves as the binding post for the connecting conductor 32. When the contact K is at the end 2 of the resistance unit R^2 for a given amplitude of radio frequency energy absorbed by the antenna A the potential of grid g of the tube V is at a maximum. To reduce the volume the contact K is moved toward the end 1 of the resistance unit which reduces the potential of the grid of the tube V, with a consequent reduction in volume of reproduction of the loud speaker. As the contact K moves along the section r^1 the resistance change per unit length of movement of the contact is of the same magnitude throughout traverse of that section, is less during traverse of section r^2 , and still less during traverse of section r^3 . The result is therefore a decrease of potential of the grid g of the tube V, as the contact K is moved from end 2 to the end 1. In the high volume region of control, adjacent the end 2, the change of resistance is relatively small per unit movement of the contact K and it requires no particular nicety of rotatable adjustment of knob 27 to effect desired change in volume. However, at the region of low volume control toward or adjacent the end 1 of the unit, to effect a given percentage change in volume requires a much smaller change in impedance and this implies a smaller or nicer adjustment of the knob 27. To obviate such need for nicety of adjustment, the impedance change per unit of movement of the contact K is much less due to the increased spacing of the section r^2 , and the double winding of section r^3 . By utilizing a plurality of sections, and of proper length with respect to each other, a smooth and gradual change in volume control is possible, and particularly in the section r^3 .

A control resistance R^2 of the character herein described may be utilized in other positions than that described. For example, such a resistance may be connected in shunt with the primary of one or more coupling transformers, as of T¹, Fig 1. The resistance may also be utilized in shunt between the input elements of a tube, as the coupling tube V, as disclosed in co-pending application Serial No. 249,785, above referred to.

It will be understood that the effect of section r^3 of the resistance R may be varied, as by change of the relative pitches of the overlying layers or coils thereof, and/or by variation of material of either coil. Furthermore the pitch of either or both coils c or d may vary as it progresses along the form. The lengths of the sections r^1 , r^2 and r^3 may vary, although if, for example, the coarse winding of section r^3 is unduly shortened, there would

be an abrupt change in volume, noticeable as a click in the loud speaker, as the contact K passes from one section to the other.

While preferably the component part c of section r³ is a coil wound on strip 3 as a form, it may consist, for example, of a coil threaded through holes 33 in strip 3, as in Fig. 7, and part d wound thereover around the edges of form 3, as before, and in such case the pitch of r⁴ and d may be the same.

What I claim is:

1. A variable resistance unit comprising overlying conductor helices, the turns of different helices intersecting and electrically 15 contacting each other, and a co-operating movable contact.

2. A variable resistance unit comprising overlying conductor helices of different pitches each having a plurality of turns in 20 electrical contact with turns of the other, and a co-operating movable contact.

3. A variable resistance unit comprising overlying electrically contacting conductor helices wound in opposite axial directions, 25 and a co-operating contact.

4. A variable resistance unit comprising overlying conductor helices, the turns of different helices intersecting and electrically 30 contacting each other, and a contact movable in engagement with the turns of the different helices.

5. A variable resistance unit comprising overlying conductor helices of different pitches in electrical contact with each other, 35 and a contact movable in engagement with the turns of the different helices.

6. A variable resistance unit comprising overlying electrically contacting conductor helices wound in opposite axial directions, 40 and a contact movable in engagement with the turns of the different helices.

7. A variable resistance unit comprising overlying electrically contacting conductor helices of different pitches wound in opposite axial directions, and a co-operating movable contact.

8. A variable resistance unit comprising overlying electrically contacting conductor helices of different pitches wound in opposite axial directions, and a contact movable in engagement with the turns of the different helices.

9. A variable resistance unit comprising a form, spaced turns of continuous conductor thereon, differently spaced turns of continuous conductor overlying said turns and in electrical contact therewith, and a contact movable in engagement with said turns.

10. A variable resistance unit comprising a form, spaced turns of continuous conductor thereon, spaced turns of continuous conductor wound over and intersecting said turns in electrical contact therewith, and a contact movable in engagement with 65 said turns.

11. A variable resistance unit comprising a form, spaced turns of conductor thereon, differently spaced turns of conductor wound over said turns in electrical contact therewith and in a reverse direction along said form, and a contact movable in engagement with said turns.

12. The method of producing a resistance unit for a volume control rheostat, which comprises winding a conductor in the form of a helix, winding over said helix a conductor helix of different pitch and in electrical contact with said first named helix.

13. The method of producing a resistance unit for a volume control rheostat, which comprises winding a conductor in the form of a helix, and winding thereon in opposite direction axially a second conductor helix whose turns intersect with and electrically 80 contact the turns of the said first named helix.

14. The method of producing a resistance unit for a volume control rheostat, which comprises winding a conductor upon and towards one end of a form, and thereafter 90 winding conductor towards the other end of said form in overlying intersecting and electrically contacting relation with said first named conductor.

15. The method of producing a resistance unit for a volume control rheostat, which comprises winding a layer of conductor upon and towards one end of a form with predetermined spacing between turns, and thereafter winding conductor with different spacing between turns towards the other end of said form in overlying and electrically contacting relation with said first named conductor.
